W. S. GRANT

CONTAINER

Filed Oct. 20, 1926

INVENTOR.
WALTER S. GRANT.

By James L. Hopkins,
ATTORNEY.

UNITED STATES PATENT OFFICE.

WALTER S. GRANT, OF ST. LOUIS, MISSOURI.

CONTAINER.

Application filed October 20, 1926. Serial No. 142,799.

My invention relates to improvements in containers and has particular relation to containers of the drum type, composed of two circular heads and a cylindrical wall.

5 The object of my invention is to provide such a container with a pouring spout inclined in the direction of the flow of the contents of the container when being poured, and to provide a vent pipe communicating directly with the bottom opening of the pouring spout and communicating with the interior of the drum at a point near the pouring spout, and extending rearwardly from the pouring spout; my preferred mounting of said vent pipe being an adjustable mounting in an annular socket formed in a baffle-plate, the baffle-plate being mounted in the inner mouth of said pouring spout.

10

Drawings.

In the drawings—

Fig. 1 is a top plan view of a container embodying my invention.

25 Fig. 2 is a longitudinal fragmental sectional view, taken on the line 2—2 of Fig. 1.

Fig. 3 is a fragmental top plan view indicating the location of the baffle-plate and vent pipe.

30 Fig. 4 is a side elevation of the baffle-plate with the vent pipe in place therein, and indicating the adjustment of the vent pipe with reference to the baffle-plate.

Fig. 5 is a bottom plan view of the baffle-35 plate and vent pipe in place.

Fig. 6 is a longitudinal vertical sectional view of the container, a portion being broken away to show the liquid content, and the container being shown in pouring position, with the inner end of the vent pipe 40 extending into the air space above the liquid.

Description.

The drum A is formed of the circular heads 7 and 8 and cylindrical wall 9, the container when in normal position resting upon its bottom and the bottom of the weighted pouring handle 9^a. At its top the container A is provided with a carrying

handle 10. Beneath the carrying handle is 50 the pouring spout 11 having a screw cap closure 12, the spout 11 being tilted forwardly in the direction of the flow of the poured contents, as shown in Fig. 2. Beneath the inner mouth of the spout 11 I 55 provide a baffle-plate 13 containing a socket 14 for the reception of the vent pipe 15. The vent pipe 15 is of any desired length and is adjustably mounted in the socket 14 as indicated by dotted lines in Figs. 4 and 5. 60

The socket 14 is formed as shown in side elevation in Fig. 4 so that it has a direct outlet through the air chamber 16 from the vent pipe 15 through the top of the baffle-plate 13 in the interior of the pouring spout 11. The purpose of this vent pipe construction is to permit the continuous flow of liquid through the spout 11 without gurgling. Beside serving as a base for the vent pipe 15, the baffle-plate 13 serves to constrict the 70 area of the pouring spout 11 as indicated in Figs. 2, 3 and 5 and thus restrict the volume of liquid being poured, as an additional aid to the free and continuous flow of the contents of the container A during the pouring 75 operation.

Variations of structure may be effected without departure from my invention as defined in the appended claims.

Claims.

80

I claim:

1. A container having a cylindrical wall, in combination with a pouring spout mounted in said wall; a baffle-plate mounted beneath said pouring spout and having a suitable receiving socket, and a vent pipe mounted in said socket.

2. A container having a cylindrical wall, in combination with a pouring spout mounted in said wall; a baffle-plate mounted beneath said pouring spout and having a suitable receiving socket, and a vent pipe adjustably mounted in said socket.

In testimony whereof I have hereunto affixed my signature.
